IGNITION DEVICE

Earl H. Shannon, Gary, Ind.

Application September 30, 1944, Serial No. 556,586

2 Claims. (Cl. 175—115)

1

This invention relates to ignition devices and more particularly to those which are operated electrically and used in connection with fuel burners.

It is common practice to provide electrical ignition devices for fuel burners so as to maintain a continuous spark whereby temporary failures in the fuel supply system will not cause explosions upon resumption of the fuel supply after such failures. An ignition device for such purpose is shown in the patent to Miss No. 2,318,408, dated May 4, 1943. Such an ignition device as shown therein consists generally of a longitudinally extending burner having a single electrode spark plug arranged in an opening intermediate the length thereof to which current is supplied from a suitable source of power. There is connected to the inner end of the center electrode of the spark plug, an elongated electrode which extends substantially perpendicular thereto and is arranged axially of the burner. On the other end of the burner there is arranged a grounded electrode at which point the spark is produced for igniting the gases issuing forth from the outer end of the burner.

A similar ignition device is shown in my pending application, Serial No. 518,269, filed January 14, 1944, and entitled "Spark plug."

In both of the above devices the ground electrode is arranged outside of the burner in the furnace, the elongated electrode extending through the burner to a point adjacent the ground electrode, thus forming a spark gap. Thus the electrodes are exposed to the heat of the furnace and in a relatively short time must be replaced. This is especially true of the ground electrode which has no means for adjustment. The burner also makes considerable noise when operating, which I have found is due to the disposition of the ground electrode in the fuel stream.

It is an object of my invention to provide an ignition device for burners in which the electrodes are protected from the heat of the furnace.

Another object is to provide an arrangement of electrodes in a tubular burner so that the noise or howl of the burner is muffled.

These and other objects will be more apparent after referring to the following specification and attached drawings, in which:

Figure 1 is a sectional view through the burner; Figure 2 is an end view thereof; and Figure 3 is a general arrangement of the burner and tube assembly.

Referring more particularly to the drawings 55 provided a spark gap directly in the path of the

the numeral 2 designates a metallic fuel feed tube having the usual inlet end 2a and outlet end 2b, the latter of which is adapted to extend within the furnace or the radiant tube assembly with which the device of the invention is to operate. At the inlet end 2a of the fuel feed tube 2 there is provided the usual means 3 for supplying gas together with an air inlet 4.

In the side wall of the fuel feed tube 2 there is 10 a screw-threaded aperture 5 which is adapted to receive the externally screw-threaded housing 6 of a conventional spark plug from which the ground electrode has been removed. Within the spark plug housing 6 there is disposed in screw-threaded engagement therewith the spark plug sleeve 7 which is adapted to hold in rigid relationship therein the porcelain insulator 8 of the spark plug, the center electrode 9 extending therethrough and well into the center of the fuel 15 feed tube 2. The extended end of the center electrode 9 is screw-threaded and carries thereon an internally screw-threaded sleeve 10 which has a cross-aperture 12 therein. This cross-aperture 12 receives an elongated electrode 13 which projects from the exit end 2b of the fuel feed tube 2. The exit end 2b of the fuel feed tube 2 is provided with a refractory cap 14 having a series of apertures 15 therein, one of which is centrally disposed to receive the extended end of the electrode 13, which does not pass completely through the cap 14. This refractory cap 14 is suitably retained in the end of the fuel feed tube 2 by means of a screw-threaded retainer cap 16 which is threaded to the end of the extension sleeve 17, 20 this sleeve being provided with a ground electrode 18 similar to that of a conventional spark plug. If desired the electrode 18 can be fastened directly to the burner body and the sleeve 17 omitted.

25 Immediately opposite the screw-threaded aperture 5 in the fuel feed tube 2 is a similar aperture 19 in which there is disposed a screw-threaded plug 20. By removing the screw-threaded plug 20 and loosening the externally-threaded sleeve 25 7 of the spark plug the porcelain insulator 8 may be rotated to relieve the set-screw effect of the electrode 9 with respect to the electrode 13 whereby the latter may be suitably adjusted. After the desired adjustment the porcelain insulator 8

30 may be rotated to again obtain the set-screw effect of the electrode 9 with respect to the electrode 13 and the externally-threaded sleeve 7 drawn tight to maintain the adjustment.

35 From the foregoing it will be seen there is provided a spark gap directly in the path of the

fuel stream wherein electrodes 13 and 18 defining said spark gap are disposed entirely within the burner in such a manner as to be removed from intimate contact with the flame and protected from the heat of the furnace tube. By virtue of the described arrangement the electrodes do not deteriorate from use and as a result the required spark gap is constantly unvariably maintained providing efficient ignition of the combustible gases with minimum adjustment and maintenance.

Referring to Figure 3 which shows a typical burner installation in which a radiant tube assembly 22 is fastened to and passes through the wall 24 of a furnace, attention is directed to the striking similarity in shape and contour of the tube assembly 22 to a tone chamber of an ordinary musical instrument. In this instance the fuel emitting from the burner produces audible noise which is increased by the myriad minute explosions occurring during combustion.

In prior art practice it is customary to provide a spark gap for ignition purposes on the outside of the burner directly in the exiting fuel stream, and in such arrangements the grounded electrode forms an obstruction which disturbs the equilibrium of the fuel stream and creates additional noise.

The complexity of noises so created, and substantially amplified by the tone chamber, cannot be properly identified with known musical tones and possesses no acoustic characteristic except that of obnoxiousness. The volume of noise as well as its tonal quality is also effected by the pressure applied to the burner, the location of the burner, and other variables too numerous to mention.

By relocating the grounded electrode 18 as shown in Figure 1 within the burner, it has been found that objectionable noises formerly present have practically disappeared, or at least have been altered in pitch or vibration frequency so as to be no longer audible. This phenomenon may be partially accounted for by the fact that the combustible mixture is already in a turbulent state within the discharge end of tube 2 caused

by the baffle effect of refractory cap 14 which obstructs somewhat the flow of the mixture. It has been pointed out that the primary audible noises occurring outside of the burner are caused to increase in magnitude by the ground electrode located in the same vicinity, but by relocating the electrode within the burner and adjacent the refractory cap 14 as shown, there is no noise creating effect on the fuel stream.

While I have shown and described one specific embodiment of my invention, it will be understood that I do not wish to be limited exactly thereto since various modifications may be made within the scope of my invention, as defined by the following claims.

I claim:

1. In an ignition device for use with a tubular burner having a perforated refractory cap on its discharge end, the combination which includes an electrode disposed within and extending longitudinally of the burner, said electrode being supported by and terminating in said refractory cap, a ground electrode disposed within the burner and located within two inches of said refractory cap and forming a spark gap with said first named electrode, and an electrical conductor extending into said burner intermediate the length thereof, said conductor supporting the inner end of said first mentioned electrode.
2. In an ignition device for use with a tubular burner having a perforated refractory cap on its discharge end, the combination which includes an electrode disposed within and extending longitudinally of the burner, said electrode being supported by and terminating in said refractory cap, a sleeve attached to the body of the burner between the end thereof and said refractory cap, a ground electrode carried by and within said sleeve and located within two inches of said refractory cap and forming a spark gap with said first named electrode, and an electrical conductor extending into said burner intermediate the length thereof, said conductor supporting the inner end of said first mentioned electrode.
